UNITED STATES PATENT OFFICE.

THOMAS T. CHALONER, OF NEW YORK, N. Y.

SAFETY DEVICE FOR STOPPING RAILWAY-TRAINS.

No. 890,214.

Specification of Letters Patent.

Patented June 9, 1908.

Application filed February 1, 1908. Serial No. 413,817.

To all whom it may concern:

Be it known that I, THOMAS T. CHALONER, a citizen of the United States of America, and a resident of the borough of Manhattan, city 5 of New York, State of New York, have invented a new and useful Improvement in Safety Devices for Stopping Railway-Trains, of which the following is a specification.

The railway train stopping device forming 10 the subject of this invention is of that class of safety appliances adapted to be located on the locomotive or in any car of railway trains and to be actuated by stationary signal devices, when set in danger position, to put in 15 action the automatic brake system of the train should the engineer overlook the danger set signal.

The object of the invention is the construction of an automatic brake applying device 20 that is simple, of few parts, strong and positive in action, adapted to receive shocks, such devices are subjected to, without injury, and to occupy but little space in the cab of a locomotive or other selected location on or 25 in any of the cars of a train.

Figure 1 represents, in elevation, the automatic brake applying device located in the cab of a locomotive. Fig. 2 is a plan view of the device, showing the air controlling valve 30 of the brake system in section. Fig. 3 is a front elevation, partly in section on line 3, 3, Fig. 2, and Fig. 4 is a side elevation of the lower part of the device, showing a modification in the arrangement of the air valve.

The body or main portion *a* is provided 35 with bearings for carrying the movable parts of the device; it is preferably a casting provided with a base by which it may be secured in any desired location, said base *b* being 40 shown in Figs. 1 and 4 shaped to enable the device to be secured to a boiler *c* in the cab *d* of a locomotive, to place the device within easy reach of the engineer.

A vertical shaft or rod *e* has its lower part 45 fitted to rock in a bearing of the body *a*, it extends through the roof of the cab *d*, where it is provided with a bearing *f*, and has secured to its upper end an arm *g*, extending beyond the side limits of the locomotive and train 50 and arranged to strike a projecting bar which is set in its path when a signal is set at "stop" or danger. A stop bar set from an overhead signaling apparatus is represented by the dotted lines *h* Fig. 1; these lines may of 55 course be taken to represent the stop bar of

any other style, as for instance a side signaling apparatus.

Now, a movable arm of the character of the arm *g* carried by a moving train would be subjected at times to severe shocks, and 60 would impart severe shocks to a signal stop bar *h*, liable to injure this stopping device and signal apparatus when these parts come in contact, and to obviate this I provide the arm *g* with buffers or cushioning means which 65 will receive the first impacts of the blows of contact, and cause the arm to be moved by the stop bar without injurious jars. These buffer means may consist of flexible plates *i*, *i* secured to the arm *g* near its inner end 70 and extending to the outer end of said arm, and springs *j*, *j* either of metal or india rubber, located between the plates *i*, *i* and the arm *g*. By making the contact surfaces of the buffers of metal, as by the plates *i*, *i*, said 75 surfaces will act on the stop bar with the least amount of friction and the buffers will be thereby subjected to minimum wear. At the lower end of the shaft *e* is secured a tappet *k*, which is located between and acts upon 80 the horns of a forked lever *l*, secured to the end of a horizontally arranged shaft *m*, having its bearing in the body *a*. The horns of the forked lever *l* are so shaped as to hold, when in vertical position, the tappet, and 85 consequently the arm *g*, in central positions, and when the arm *g* is moved to either side by contacting with the bar *h*, the forked lever *l* and its shaft is correspondingly rocked. Now as there is more or less swaying of locomotives and railway cars when in motion the 90 stationary bar *h* will strike the arm, or the side plates *i*, *i*, at distances variable from the fulcrum of the arm *g*, as indicated by the arrows *n*, *n*, and as the smallest arc through 95 which said arm will be moved is when the bar *h* strikes the arm at the greatest distance from the fulcrum, the forked lever *l* is then set, in either direction, by the tappet *k* at the full distance it is designed to be moved, and 100 any further movements of the tappet due to the bar *h* striking the arm *g* closer to its fulcrum will not further move the forked lever, as the upper parts of its horns are so shaped 105 as to permit the tappet to slide along them and hold the forked lever in set position, as clearly shown by the dotted lines *y*, Fig. 3.

A hand lever *o* is secured to the shaft *m*, or to the forked lever *l*, and by means of 110 which the engineer or other train attendant,

- according to the location of the device on the train, may set the device in normal inactive position after it has been actuated by a signal bar *h*; said hand lever when so set then being 5 in a vertical position, and to hold it there a suitable locking device is provided, as for instance a spring actuated latch *p* of any suitable ordinary construction. It will be understood that when this actuating mechanism 10 is of a train stopping device is set in operative position by a signal stop bar a controlling device of the brake mechanism, as a valve of an automatic air brake system, will be opened to permit the brakes to be automatically applied. Such a valve may be located in any suitable place and is represented at *q*, Figs. 2 and 3, as a face valve *s* whose stem is provided with an arm *r*, connected to the hand lever *o* by the link *t*. This valve is 15 provided with a port *u*, which is cut off when the device is in normal inoperative condition, as shown at Fig. 2, but is open to one of the stationary ports *v* when the arm *g* is moved by a stop bar *h*, according to the direction of 20 movement of the train, so as to allow the active brake fluid, as compressed air, to flow through the pipes *w* and *x* and so allow the brake system of the train to become active. This operating valve *q* may be attached to, 25 or its case form a part of, the body *a* of the device, with its valve *s* secured directly to the end of the horizontal shaft *m*, as shown at Fig. 4. This arrangement forms a very simple and compact apparatus; but it will be 30 understood that the location of the valve, as well as that of the operating device will be determined by the requirements of the application of this train stopping mechanism to railway trains.
- 40 It will be observed that the structure here described meets the aims and objects of the invention; having few parts, simplicity, ease of construction and application, positive action, need of but little space, great strength, 45 and non-liability to damage from sudden impacts with stationary stop bars.

I claim as my invention:

1. In a safety device for stopping railway trains, a movable arm provided with buffers or cushioning means comprising a metallic contacting surface on each of its sides, carried by and projecting outside the train, whereby it is adapted by either of its sides to contact with and be moved by a set stationary stop bar and be moved either way from a central position without injurious shocks; in combination with the brake system of the train; and means connecting the arm to a controlling device of the brake system.
- 60 2. In a safety device for stopping railway trains, an arm carried by and projecting outside the train adapted to be rocked from central or normal position by contacting with a set stationary stop bar; a tappet connected to and moved in unison with the arm; a

forked lever actuated by the tappet and shaped to be moved its full distance when the arm and tappet rock through the smallest arc of their movements, and to be retained in such position when the arm and tappet are 70 moved through a greater arc; in combination with the brake system of a train; and means connecting the forked lever to the controlling device of the brake system.

3. In a safety device for stopping railway 75 trains, an arm carried by and projecting outside the train adapted to be rocked in either direction from central or normal position by contacting with a set stationary stop bar; a tappet connected to and moved in unison 80 with the arm; a forked lever actuated by the tappet and shaped to be moved its full distance in either direction when the arm and tappet rock through the smallest arcs of their movements, and to be retained in such 85 position when the arm and tappet are moved through greater arcs; in combination with the brake system of a train; and means connecting the forked lever to the controlling device of the brake system. 90

4. In a safety device for stopping railway 95 trains, a movable arm provided with buffers or cushioning means, carried by and projecting outside the train, whereby it is adapted to contact with and be moved by a set stationary stop bar without injurious shocks; in combination with a tappet connected to and moved in unison with the arm; a forked lever actuated by the tappet and moved into 100 fixed positions in opposite directions and held in such positions by further movements of the tappet; the brake system of the train; and means connecting the forked lever to a controlling device of the brake system.

5. In a safety device for stopping railway 105 trains, an arm carried by and projecting outside the train adapted to be rocked in either direction from central or normal position by contacting with a set stationary stop bar; a tappet connected to and moved in unison 110 with the arm; a forked lever actuated by the tappet and shaped to be moved its full distance in either direction when the arm and tappet rock through the smallest arcs of their movements and to be retained in such 115 position when the arm and tappet are moved through greater arcs; in combination with a resetting hand lever connected to or forming a part of the forked lever, and a locking device for holding it in normal inoperative position; the automatic brake system of the train provided with a double acting controlling valve; and a link connecting the forked lever to said controlling valve. 120

6. In a safety device for stopping railway 125 trains, a movable arm provided with buffers or cushioning means comprising a metallic contacting surface on each of its sides, carried by and projecting outside the train, whereby it is adapted by either of its sides to 130

contact with and be moved in the two directions from a central position by a set stationary stop bar without injurious shocks; in combination with the automatic brake system provided with a controlling valve; a shaft extending from the interior to exterior of the cab of the locomotive or other vehicle of the train and to the outer end of which the arm is connected; and means connected to the controlling valve of brake system through medium of device attached to the inner end of the shaft.

7. In a safety device for stopping railway trains, a movable arm provided with buffers or cushioning means, carried by and project-

ing outside the train, whereby it is adapted to contact with and be moved by a set stationary stop bar without injurious shocks; in combination with the brake system of the train; means connecting the arm to a controlling device of the brake system; and a hand lever for resetting, and means for holding the arm in central normal position.

In testimony whereof, I have hereunto subscribed my name, this 30th day of January, 1908.

THOMAS T. CHALONER.
